[57] **CLAIM**

The ornamental design for an inkjet printer with an auxiliary sheet feeder, as shown and described.

DESCRIPTION

FIG. 1 is a perspective view of an inkjet printer with an auxiliary sheet feeder in accordance with the present invention;

FIG. 2 is a top plan view thereof;

FIG. 3 is a front elevational view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines in FIGS. 1-4 and 6 are for illustrative purposes only and form no part of the claimed design.
